UNITED STATES PATENT OFFICE.

HENRY AUCHU, OF EMPORIUM, PENNSYLVANIA.

MACHINE FOR PACKING DYNAMITES AND OTHER HIGH EXPLOSIVES INTO SHELLS.

1,074,923.

Specification of Letters Patent.

Patented Oct. 7, 1913.

Original application filed July 26, 1910; Serial No. 578,993. Divided and this application filed November 28, 1910. Serial No. 594,552.

To all whom it may concern:

Be it known that I, HENRY AUCHU, a citizen of the United States, residing at Emporium, county of Cameron, and State of Pennsylvania, have invented certain new and useful Improvements in Machines for Packing Dynamites and other High Explosives into Shells, of which the following is a specification.

10 This invention relates to machines for packing dynamites and other high explosives into shells which may be conveniently used for blasting and other purposes, this application being a division of my application, Serial No. 578,993, filed July 26, 1910.

Dynamites and other high explosives are most frequently packed into paper shells by hand on account of the extreme danger of the operation.

20 The present invention has for its object the provision of a novel machine, susceptible of many modifications, which will be adapted to automatically, rapidly and safely carry out the operation of packing the shells and 25 whereby a number of shells may be simultaneously packed, but the packing operation of each will be independent of the others, so that each shell will be satisfactorily packed or filled.

30 In carrying out the invention, I provide means for gently but regularly packing the shells with the explosive; means for feeding the explosive to the packing devices; means for regulating the pressure of the 35 packing action; means whereby the packing operation will cease automatically when a shell is filled and which will permit any of the packing devices to stop when their shells are filled without interfering with the continuation of the packing of the remaining 40 shells which have not been filled, together with various other improved and novel instrumentalities, as will more fully appear hereinafter.

45 In the accompanying drawings:—Figure 1 is a side elevation, a part of the hopper being in section; and Fig. 2, a front elevation.

The frame-work of the machine is shown 50 at 1, and 2 is an inclined hopper carried thereby which is provided with an open front and a wall 3.

The numeral 4 designates a feeder which has spurs or paddles 5 operating in the 55 lower front part of the hopper and adapted

to gently urge the dynamite or other high explosive toward the feeding devices and into the shells. The inclination of the hopper bottom may be changed as desired, according to the consistency or nature of the explosive to be operated upon, so that the 60 gravitational action thereof will carry such explosive downwardly and forwardly to the feeder. The front part of the hopper bottom adjacent to the wall 3 is provided with any desired number of funnel shaped openings in which the removable funnels 6 are placed, the paper shells to receive the dynamite or explosive being shown at 7 and held in a split or divided holder 8, which is suitably supported by the frame 1. A number 65 of these holders 8 may be employed in which the operator will place the shells 7 so that as soon as one set is filled, the holder and the filled shells may be quickly removed and another holder with empty shells inserted 70 in place thereof, thus insuring great rapidity of operation without any loss of the explosive. On separating the halves of the holder 8, the shells may be removed. 75

There are employed reciprocating packers 25, preferably of wood or soft material, one for each shell, having packing feet 26 at their lower ends. These reciprocating packers are suitably guided in the frame-work 1 80 and have upper brass rods 25^a which are provided with set collars 13 having set screws and adapted to be slid up or down thereon and secured at any desired point. These collars, according to their disposition, 85 will engage one of the bearings 9 and limit the downward movement of the packers 25 and by their adjustment, the packers may be arranged to initially go down just far enough in the shells, when operated, to insure even and regular packing of the explosive therein from the bottom up. The removable disk weights 18 may be as many as it is desired to use according to the packing pressure requisite to properly tamp or pack 100 the explosive in the shells. According to the number of these disk weights or the avoirdupois thereof, the effective packing pressure may be regulated and means are thus always provided to accommodate the 105 machine to any particular explosive which is being packed. If the weights 18 are not supported by the gage collars 13, they may be otherwise suitably arranged on the packers. 110

Pivoted at 27 to the frame 1 are levers 28, corresponding in number with the packers 25, and independently connected thereto by links or connecting rods 29. The operating 5 shaft 30 carries any suitable cams 31, one for each lever 28 and the rotation of this shaft 30 causes the cams to impart an upward movement to the packers 25, the weights causing the packers to descend and 10 to gently but suitably pack the explosive in the shells. The parts are so arranged and proportioned that when the shell is filled, the lever 28 is positioned so that the cam 31 of that particular packing apparatus cannot 15 touch it and hence its cam will rotate without operating that particular packer. Each packing device is a unit and operates independently of the remaining packers, so that the rate of filling of the different shells may 20 vary and some may be completely packed before others have been filled.

Having thus described my invention, what I claim as new and desire to secure by Letters Patent, is:—

25 1. In a shell packing or filling machine, the combination with a machine frame, of a shell holder, a packer or tamper slidably mounted on said frame, operating means for said packer, a set collar adjustable lengthwise of the packer or tamper and positioned 30 to engage the frame and limit the entry of the packer in a shell held by said shell holder, means for operating the packer or tamper, and a cam adapted to coöperate

with said means to operate the packer or tamper, said cam and means being relatively so arranged that they cease to coöperate with each other when the shell is filled.

2. In a shell packing or filling machine, the combination with a shell holder, of a reciprocating packer or tamper, a lever operatively connected thereto, and a cam adapted to operate the lever, the cam and lever being so related that when the shell is filled, the cam and lever will be out of coöoperative relation.

3. In a shell packing or filling machine, the combination with the machine frame, of a shell holder, a slidably mounted packer or tamper, a collar carried thereby and adjustable lengthwise thereof adapted to engage the frame to limit the entry of the packer in the shell, a plurality of independently removable weights mounted on the collar by which the pressure the packer applies to the explosive may be regulated, a lever for operating the packer, and a cam for moving the lever, said cam and lever being so arranged that when the shell has been loaded they will be out of engagement whereby the movement of the packer will stop.

In testimony whereof, I hereunto affix my signature in presence of two witnesses.

HENRY AUCHU.
